(57) **CLAIM**

The ornamental design for spectacles, as shown and described.

DESCRIPTION

FIG. 1 is a perspective view of spectacles, showing my new design;

FIG. 2 is a front view thereof;

FIG. 3 is a rear view thereof;

FIG. 4 is a side view thereof;

FIG. 5 is a side view thereof, opposite that of FIG. 4;

FIG. 6 is a top view thereof;

FIG. 7 is a bottom view thereof;

FIG. 8 is an enlarged perspective view of the distal end of one of the temple elements of FIG. 8;

FIG. 9 is an enlarged side view of the temple element of FIG. 4; and,

FIG. 10 is an enlarged top view of one of the temple elements of FIG. 7.

The broken lines shown in the drawings of spectacles are for the purpose of illustrating the environment and form no part of the claimed design.

1 Claim, 10 Drawing Sheets
